Primary Examiner — Khawaja Anwar*Assistant Examiner* — Mojtaba Tehrani(74) *Attorney, Agent, or Firm* — Hahn Loeser & Parks LLP(57) **CLAIM**

The ornamental design for a caliper cover, as shown and described.

DESCRIPTION

FIG. 1 is a perspective view of a caliper cover, showing the new design;

FIG. 2 is a top view thereof;

FIG. 3 is a front view thereof;

FIG. 4 is a left side view thereof;

FIG. 5 is a right side view thereof;

FIG. 6 is a rear view thereof; and,

FIG. 7 is a bottom view thereof.

Broken lines in the drawings depict unclaimed portions of the caliper cover and form no part of the claimed design.

1 Claim, 3 Drawing Sheets(56)
